UNITED STATES PATENT OFFICE.

ANDREW MICHAK, OF RHONE, PENNSYLVANIA.

DESIGN FOR A FIRE-HOSE CONNECTION.

44,380.

Specification for Design.

Patented July 22, 1913.

Application filed May 13, 1913. Serial No. 767,449. Term of patent 7 years.

To all whom it may concern:

Be it known that I, ANDREW MICHAK, a citizen of the United States, residing at Rhone, in the county of Luzerne and State of Pennsylvania, have invented a new, original, and ornamental Design for a Fire-Hose Connection, for which the following is a specification, reference being had to the accompanying drawing, forming part thereof.

The figure is a plan view of a fire hose connection, showing my new design.

I claim:

The ornamental design for a fire hose connection as shown.

ANDREW MICHAK.

Witnesses:

JOS. KRENNER,
STEPHEN J. SHEFTZ.
